CLAIM

The ornamental design for a prayer wish creation and storage box, as shown and described.

DESCRIPTION

FIG. 1 is a perspective view of the prayer wish creation and storage box of this design with the lid closed;

FIG. 2 is a front view thereof;

FIG. 3 is a left side view of the device of this design;

FIG. 4 is rear view thereof;

FIG. 5 is a top plan view of the box with the lid closed;

FIG. 6 is a bottom plan view thereof;

FIG. 7 is a right side view of the device of this design;

FIG. 8 is a view similar to FIG. 1, but with the box lid in open position and the retractable handle extended;

FIG. 9 is a top plan view with the lid open and the handle extended; and,

FIG. 10 is a closeup view of a portion of the design as seen in FIG. 8.

The broken lines in FIGS. 8 and 9 are for illustrative purposes only and forms no part of the claimed design.
